BINDING DEVICE

Charles E. Emmer, Chicago, Ill., assignor to Cer-
cla, Inc., Chicago, Ill., a corporation of Illinois

Application May 12, 1937, Serial No. 142,094

3 Claims. (Cl. 281—25)

This invention relates to improvements in binding devices, particularly of the type disclosed in my application Serial No. 41,679, filed September 23, 1935, and issued into Patent No. 2,123,625, dated July 12, 1938.

The object of the invention is to produce an improved and simplified binding device formed of relatively thin sheet metal or of plastic or other suitable material.

10. The binding device of my invention is disclosed on the accompanying drawing, in which:

Figure 1 is a plan view of a sheet material blank from which the binding device is formed;

Figure 2 is an end view of the completed binding device;

Figure 3 is a plan view of a sheet blank showing a modified arrangement; and

Figure 4 is a perspective view of the binding device formed from the blank shown on Figure 3.

20 Referring to Figure 1, the sheet blank may be of metal or of plastic material and comprises a base portion or strip 10 having arms 11 extending at right angles from one edge thereof and spaced apart longitudinally of the base portion or strip.

25 The base portion or strip may have one or more arms so as to form a single ring when bent into shape or a binding device having several rings.

Referring to Figure 2, the base portion or strip 10 is folded together longitudinally to be of 30 S-shape in cross section to provide an outer wall 12, an intermediate wall 13, and an inner wall 14, the intermediate and outer walls being preferably in contact with each other, but the intermediate and inner walls being spaced apart to provide a recess 15. In other words, the base portion or strip is bent to S-shape to form a closed loop defined by the outer and intermediate walls 12 and 13, and the open loop 15 between the intermediate and inner walls. The recess 15 provided

40 by the open loop receives the free ends of the arms 11 which are bent around to ring form, as clearly shown by Figure 2. Before the rings are closed, they are extended through the perforations in the sheets to be bound and then the ring ends are extended into the recess 15 to be retained in closed position. The width of the recess 15 may 45 be so gauged that the arm ends after insertion therein will be frictionally held, or the walls of

the loop may be pressed together into frictional engagement with the ring ends.

When comparatively light sheet material is used, the ring-forming arms may be strengthened and stiffened by being provided with flange or tab portions 11' which are folded over against the inner faces of the arms, as clearly shown by Figure 3, the flanges terminating short of the ends of the arms so as to leave the arm ends of single thickness for projection into the recess 15 10 of the base portion 10, as clearly shown by Figure 4. If desired, the flanges 11' may extend to the ends of the arms and the recesses 15 then made of sufficient width to receive the ring ends.

While I have shown and described certain embodiments of my improvement for the purpose of illustration, I do not desire to be limited thereto, as changes may be made without departing from the spirit and scope of the invention.

I claim:

1. A binding device comprising a longitudinal strip bent and folded together longitudinally to be of S-shape in cross section to provide an outer wall, an intermediate wall, and an inner wall, said intermediate and inner walls being spaced apart to provide a recess, arms extending from one edge of said strip and bent to surround said strip for insertion of their free ends into said recess to form closed binding rings.

2. A binding device comprising a longitudinal strip, arms extending from one edge of said strip and bent to surround said strip to form binding rings, the intermediate longitudinal portion of said strip being bent inwardly against said strip and the inner longitudinal portion of the strip being bent outwardly into parallelism with the intermediate portion but being spaced therefrom to leave a longitudinally extending recess into which the ends of said ring forming arms are inserted to be frictionally held therein.

3. A binding device comprising a ring formed by bending a flat strip, said ring at one end being bent to S-shape to form a closed loop and an open loop, said open loop adapted to receive the other end of said ring to thereby frictionally hold the ring closed.

CHARLES E. EMMER.
